CLAIM

The ornamental design of an electrical connector for power cable, as shown and described.

DESCRIPTION

FIG. 1 is a right perspective view of an electrical connector for power cable showing our new design;

FIG. 2 is a right side elevation view thereof;

FIG. 3 is a left side elevation view thereof;

FIG. 4 is a top plan view thereof;

FIG. 5 is a bottom plan view thereof; and,

FIG. 6 is an end elevation view thereof.

The broken line portions of the figure drawings are included to show unclaimed subject matter only and form no part of the claimed design.
